CLAIM

The ornamental design for a combined sectional sofa with end tables and corner table, as shown and described.

DESCRIPTION

FIG. 1 is a top front perspective view of a combined sectional sofa with end tables and corner table showing my new design;

FIG. 2 is a top plan view;

FIG. 3 is a front elevational view; and,

FIG. 4 is a left side elevational view thereof.

The sides of the article not shown are plain and unornamented.

FIG. 2.

FIG. 3.

FIG. 4.
